STICK FILE

Filed Nov. 22, 1926

H.R. Shekerjian

By Horace N. Andree

Attorney

UNITED STATES PATENT OFFICE.

HRANT R. SHEKERJIAN, OF ATLANTIC CITY, NEW JERSEY.

STICK FILE.

Application filed November 22, 1926. Serial No. 149,988.

This invention relates to new and useful improvements in files, and particularly to the class of devices known as stick files.

- Stick files are ordinarily manufactured in two forms, one for use on a desk, or table, and known as an upright file, and the other adapted to hang on a wall, with the stick or pin extending outwardly and upwardly from the base thereof.
- 10 The principal object of the present invention is to provide a stick file which is capable of easy and quick adjustment, whereby the device may be used, in an upright position, on a desk, or may be used as 15 a wall file.

Another object is to provide novel means for holding the base of the stick or pin on the file base, so that said pin may be moved into either of its different positions.

- 20 Other objects and advantages will be apparent from the following description when taken in connection with the accompanying drawing.

In the drawing:

- 25 Figure 1 is an elevation of a stick file made in accordance with the present invention, and in the position when used as an upright or desk file.

- Figure 2 is an enlarged vertical sectional view on the line 2—2 of Figure 1.

Figure 3 is an elevation of the device when adjusted for use as a wall file.

Figure 4 is an end view of the flexible arms, showing the position of the tabs 15.

- 35 Referring particularly to the accompanying drawing, 10 represents a base, which is of the ordinary upwardly tapering type, and preferably formed of cast metal. In the upper face, or table 11, of the base, there is 40 formed an opening 12, which registers with the opening 13, in the angular U-shaped spring member 14, to receive a rivet 15, by means of which the parts are firmly fixed together. Formed on the opposite edges of 45 the arms of the U-shaped member 14 are the angularly extending tabs 15, which are spaced apart for a purpose which will presently appear. In the center of each of the said arms, or wings, there is formed a small 50 circular opening 16. Disposed within the space between the arms of the member 14 is an angular block 17, having the trunnions 18 on opposite sides, which engage in the before-mentioned openings 16, and on which 55 said block is adapted to have pivotal movement. Secured in the upper face of the

block 17 is the base of the stick or pin 19. The arms of the member 14 are preferably springy, and exert inward pressure against the block 17, whereby to confine the block 60 with the pin in a position vertical to the base, at times, and in a position horizontal, or parallel to the base, at times, this latter position being between the upper and lower tabs 15, and transversely of the arms of 65 said member. The block may be snapped from one position to the other, by spreading the arms of the member 14, with one hand, and grasping the stick or pin 19, with the other and then swinging the stick and block 70 in the desired direction. When the pin and block are in upright, or vertical position, the file is adapted for use on the desk, and when swung into a position at right angles thereto, the file is adapted to be hung on a wall, the 75 pin assuming a vertical position parallel to said wall.

By means of the construction above described, the one-stick file is capable of use in either of the positions in which such files 80 are used. The change from one position to the other may be effected without any effort on the part of the user, and without the use of any bolts or nuts, or adjusting screws, the pin being grasped and swung to 85 the desired position while at the same time the user spreads the arms of the member 14 apart to permit the block to clear the tabs 15. The base is provided with an opening 20, adjacent its periphery, to permit passage of a nail, or other device, for suspending 90 the device on the wall.

What is claimed is:

1. A stick file including a base, gripping jaws mounted on the base, and an impaling pin having a base member disposed between and movably connected with the jaws whereby to permit movement of the pin to extend longitudinally from the jaws, at times, and transversely thereof, at times, 100 said jaws being adapted to positively hold said base member in such positions.

2. A stick file including a base, spring jaws on the base, an impaling pin having an angular base pivotally supported between 105 the jaws, said jaws being formed to hold the base of the pin so that the latter will extend longitudinally from the outer ends of the jaws, at times, and transversely of the jaws, at times.

3. A stick file including a base, spring jaws on the base having spaced inner and

outer tabs on the sides thereof, and an impaling pin having an angular base pivotally supported between the jaws and arranged to be swung into positions between the tabs 5 whereby the pin extends longitudinally from the ends of the jaws, at times, and to be held between the inner and outer tabs, at times, whereby the pin extends transversely of said jaws, said jaws being manually flexible 10 to permit pivotal movement of the pin.

4. A stick file including a base, spring jaws mounted on the base, and an impaling

pin having a base member disposed between and pivotally connected with the jaws and adapted to be held thereby in positions at 15 right angles to each other, said jaws being adapted to be flexed away from each other to permit pivotal movement of the base member and impaling pin so that the latter will extend longitudinally from the jaws, at 20 times, and transversely thereof, at times.

In testimony whereof, I affix my signature.

HRANT R. SHEKERJIAN.
